UNITED STATES PATENT OFFICE.

ANNIE SEMONITE, OF BROOKLYN, NEW YORK.

TOILET-CASE.

SPECIFICATION forming part of Letters Patent No. 694,497, dated March 4, 1902.

Application filed May 15, 1901. Serial No. 60,336. (No model.)

To all whom it may concern:

Be it known that I, ANNIE SEMONITE, a citizen of the United States and wife of George E. Semonite, residing in the borough of Brooklyn, in the city of New York, in the county of Kings and State of New York, have invented a new and useful Improvement in a Combined Veil-Holder and Pincushion, of which the following is a specification.

10 Ladies veils when used become crumpled, and it is desirable that after use they should be smoothed out and nicely folded and kept in a convenient place in compact form.

15 The object of my invention is to accomplish such purpose; and it consists, briefly, of means for retaining the folded veil or veils in place and holding the same in stretched condition, combined with means for inclosing it or them thereafter without intrusion, and also 20 combined with cushions adapted to receive pins, &c.

25 In the drawings, Figure 1 is a perspective view of my invention with the case open. Fig. 2 is an end view of the same with the case closed. Fig. 3 is a central vertical longitudinal section of the same with the case closed, and Fig. 4 is an end elevation and partial vertical section on the plane of the line 4-4 in Fig. 3.

30 In the drawings, 1 is the base of the device. In the form of my invention shown in the drawings it forms the upper half of a cylindrical shell 2, the purposes of which will presently appear. The base 1 is provided with 35 upwardly-extending pins 3 3 3, which should be firmly held in place by any suitable means. The shell 2 is made open at each end and is closed by padded plugs 4 4, having an outer surface 5, adapted to fit snugly within the 40 shell, and an end surface 6, made of some suitable fabric, while its interior is filled with hair or sawdust 7, kept in place by a screen 8. These padded plugs form pincushions, into which may be stuck hat-pins 9, such as 45 are used to pin veils to ladies' hats. The cylindrical shell 2 is provided with two upwardly-extending case or purse jaws 10 10, hinged to swing upon the shell in any suitable manner and terminating in an upper edge or frame 50 11, provided with a suitable fastening device, as 12. In the form of my device illustrated the case-jaws are secured to rings 13, encir-

cling the shell 2; but any equivalent means may be employed to accomplish the same purpose. The whole device is provided with feet 55 or standards, as 14, or it may be made without such additional support.

The manner of using my device is as follows: The veil is stretched in the hands by holding its longest sides firmly and slowly and 60 firmly stretching the fabric. The part so stretched is then pressed downward over the pins 3, which are preferably arranged in a line at right angles to the longest sides of the veil. The portion of the veil which has been 65 so pressed is shown at *a* in Fig. 4. The veil is then folded as at *b* and a second section *c* is pressed downward over the pins. It is again folded as *a d* and another section *e* pressed downward over the pins and so on until the 70 veil has all been passed over the pins, then the jaws 10 10 are brought upward and closed. Of course a plurality of veils may be superimposed one above the other. The pins keep the stretched portions of the veil in the desired position and keep them folded and clean. 75

The shell 2 is preferably made hollow, so as to admit of the reception of the pins 9; but it may be stuffed like the plugs or end 80 pieces. The shell may be made of any suitable material—such as metal, wood, leather, or celluloid—and so may the case-jaws and standards. The whole forms a pleasing addition to a traveler's outfit or a lady's dressing-case. 85

What I claim as new is—

1. A device for holding a veil or the like in transversely-stretched condition, comprising a base, a series of pins projecting upward 90 from said base and arranged in a straight line with each other along the length thereof, whereby each section of a transversely folded and stretched veil may be impaled upon all of said pins and held thereby, and 95 a cover adapted to inclose said veil and pins substantially as described.

2. A device for holding a veil or the like in transversely-stretched condition, comprising a series of lineally-arranged pins upon 100 which the folded veil is impaled and by which it is held in extended position, a base supporting the pins and veil, pivoted jaws coöperating to form a compartment wherein said

pins and the veil are contained, and means for detachably securing said jaws together to inclose said pins and veil.

3. A combined pincushion and veil-holder, 5 or the like, comprising a base having an opening extending longitudinally through it and provided with a series of outwardly-extending pins which rise from the surface of said base and upon which a folded veil may be 10 impaled and held in transversely-stretched condition, and cushions applied to said base and closing the ends of the opening therethrough, substantially as described and for the purposes specified.
- 15 4. A combined pincushion and receptacle for ladies' veils or the like, consisting of a hollow base, having cushioned ends and provided with a series of rigid outwardly-extending pins upon which a folded veil may 20 be impaled and by which the same may be held in transversely-stretched condition, and hinged jaws coöperating to inclose the series of pins and the material impaled thereon.
5. A combined pincushion and receptacle 25 for ladies' veils and the like, consisting of a base, a pincushion applied to the end of said

base, a series of pins rising from said base and so arranged that a folded veil may be impaled thereon and held thereby in transversely-stretched condition, a pair of jaws 30 pivoted at their lower ends to opposite sides of said base and rising therefrom so as to inclose said pins and the material impaled thereon, and means for detachably securing the upper ends of said jaws together. 35

6. A combined pincushion and veil-holder, comprising a suitably-supported hollow base provided with a line of pins which project upward from its upper surface and are adapted to hold a folded and stretched veil, as specified, and a padded plug fitted to an end of said base and closing the same, said plug having its inner end located within the base and provided with a screen. 40

Witness my hand, this 14th day of May, 45 1901, in the presence of two subscribing witnesses.

ANNIE SEMONITE.
